UNITED STATES PATENT OFFICE.

BARNEY SAMUELS, OF ST. JOSEPH, MISSOURI.

ELECTRIC RAILWAY SIGNALING SYSTEM.

SPECIFICATION forming part of Letters Patent No. 601,482, dated March 29, 1898.

Application filed May 6, 1896. Serial No. 590,489. (No model.)

To all whom it may concern:

Be it known that I, BARNEY SAMUELS, a citizen of the United States, residing at St. Joseph, in the county of Buchanan and State of Missouri, have invented certain new and useful Improvements in Electric Railway Signaling Systems; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain new and useful improvements in railway-signals, and applies more particularly to that class which are employed in connection with the block system.

20 The invention has for its object to provide an electric railway-signal which will be simple and cheap in construction and economical in its operation and by means of which the excess of battery consumption usually existing 25 in signals of this class will be largely overcome.

The invention will be hereinafter fully set forth, and particularly pointed out in the claims.

30 In the accompanying drawings, Figure 1 is a side view of the double-casing signal. Fig. 2 is a front face view of a single casing, the front of the casing being removed. Fig. 3 is a view illustrating the electric circuits for 35 one single block of track. Fig. 4 is a simplified form of my preferred system for one single block of track. Fig. 5 is a diagrammatical view of a continuous block-signaling system. Fig. 6 is a view of a slightly-modified form 40 thereof. Fig. 7 is a view illustrating the system shown in Fig. 5 as adapted for use on double tracks. Fig. 8 illustrates the system for controlling the track-circuits in the event of poorly-insulated track-sections. Fig. 9 is a 45 view illustrating the system for controlling two signals at a switch. Fig. 10 is a similar view of a system for controlling one signal.

Referring to the drawings, Figs. 1 and 6, the signal proper consists of casings A and A', 50 mounted on a post a', adjacent the railway-track and provided with a central cut-away portion a², in which is located a lamp a³.

Each casing is provided with a compartment a⁴, in which is located the signaling apparatus hereinafter described. The other figures show 55 a single casing, which has a lamp back of same, as in Fig. 2. An arm or lever b is pivoted at b' to a suitable arm or bracket b² and provided with signal-disks B B', one on each end, said disks being designed to normally 60 cover openings b³ b⁴ in the casing, the disk B being known as the "day-signal," while disk B' is translucent to allow the light from lamp a³ to pass therethrough and is useful only as a "night-signal." The pivot b' of arm or 65 lever b serves as an armature-shaft for an ordinary Z-armature b⁵, rotating between the poles of a magnet b⁶, which is energized by a powerful battery b⁷, located at any suitable or convenient point, one pole of which is directly connected to said magnet by means of a wire b⁸. The other pole of said magnet is connected by a wire b⁹ to a spring-electrode b¹⁰, the spring-arm b¹² of which normally holds the same in contact with a stationary electrode b¹³, secured to the casing and connected by a wire b¹⁴ to a similar electrode b¹⁵. C is 70 a pivoted arm connected by a wire to magnet b⁶ and provided with a counterbalancing-weight b¹⁶, which normally holds the contact-point 75 b¹⁷ of said lever away from electrode b¹⁵, said lever being adapted to contact with said electrode when said signal is operated.

D is a magnet mounted adjacent the lower end or armature d of lever C, said magnet being 85 operated by the track or wire circuits, the current passing in and out through wires d' d². In practice when a current of electricity passes through magnet D the same will attract the armature on lower end d of arm C, 90 and thereby bring the contact-point b¹⁷ thereof in contact with electrode b¹⁵, whereupon the current from battery b⁷, acting on armature b⁵, will cause the rotation of arm or lever b until the same reaches the position illustrated in Fig. 2. Said lever in its movement, 95 however, will open the circuit from battery b⁷, because of a hook arm or member d³ thereof engaging the outer hooked end d⁴ of electrode b¹⁰ and moving the contact-point thereof away from electrode b¹⁵. As soon as this 100 circuit is again opened lever b would tend to return to its normal position; but the same is held in its abnormal position as long as cur-

rent is passing through magnet D by means of an armature d^5 on said lever being attracted and held by said magnet. When the current is cut off from magnet D, the arm or lever b will gravitate back to its normal vertical position. In hereinafter referring to the two positions of lever b I shall term the normal or vertical position of the same as "danger," while the abnormal or horizontal position thereof will be termed "safety."

In Fig. 3 I have illustrated a system for operating my signal in connection with one single block of track. In this form I employ two signals A A', one on each side of the track at each signal-station. In this form the wire d' from signal A is connected at e to a circuit-wire e' , which at one end is connected to one pole of a battery 1, while the other end thereof is connected to one of the rails E of the railway-track. The wire d^2 of said signal is connected direct to an electrode e^2 . The battery 1 has its other pole connected by a wire e^3 to a second electrode e^x , directly opposite electrode e^2 . With electrode e^x is designed to normally contact one end of a pivoted arm or armature e^4 , which is so held by a magnet e^5 , connected by wires e^6 to the rails of a short section of track E', the rails of which are electrically charged by means of a battery 2. A second short section of track E' is electrically charged by means of a battery 3, the current therefrom passing through a second magnet e^7 , which normally holds a pivoted arm or armature e^8 in contact with an electrode e^9 , which is connected by a wire e^{10} to the other rail E' of the main track-section. The pivoted armatures e^4 and e^8 are electrically connected by means of a wire e^{12} or any other suitable means. The wires d', d^2 of signal A' are connected to wires e^{13} and e^{14} , the former of which is connected to an electrode e^{15} opposite electrode e^9 , and the latter being connected to wire e' . The set of signals just described I will designate "signal-station S." At the other end of the block is located a second signal-station S', in which the signals and circuit-wires are identical with those just described.

In operation when the wheels of a train 50 pass onto the rail-section E' said wheels will short-circuit battery 2 and allow the pivoted armature e^4 to move from contact with electrode e^x to electrode e^2 , whereupon current will pass from battery 1 of station S', through armatures e^4 and e^8 of said station, to wire e^{16} thereof, and thence through track or rail E' to wire e^{10} of station S. From thence it will pass through the arms or armatures e^8 and e^4 of said latter station to wire d^2 of signal A, and thence out through wires d' and e' to rail E' of main section, and thence through wire e' of station S' to battery 1 of said station, thereby operating signal A and bringing the same to "safety." As said wheels pass from section E' to section E' arm e^4 will again be drawn back to its normal position and armature e^8 of station S will be caused

to drop because of the short-circuiting of battery 3 of said station, whereupon signal A' of said station S will be operated by the current from battery 1, passing through armatures e^4 e^8 to wires e^{13} and d' of said signal and back through wires d^2 , e^{14} , and e' to said battery. Meanwhile the signals of station S' cannot be operated because of the use of battery 1 of station S in operating the signal A' thereof. As the wheels pass onto the main track-section the armature e^8 resumes its normal position and the current from station S would be free to operate signals at station S' but for the fact that said wheels will short-circuit the battery 1 of each station, thereby maintaining all the signals at "danger," the signal A' at S, just referred to, not being used by trains going from left to right on the diagram just described. As the wheels pass onto section E' of station S' the armature e^8 of said station contacts with electrode e^{15} and in that way closes circuit from battery 1 of said station, thereby operating signal A' thereof. As said wheels pass onto section E' of said station arm or armature e^4 thereof will contact with its electrode e^2 , thereby closing the circuit from battery 1 of station S and operating signal A of station S' in a manner similar to the operation of the same signal at station S. As soon as the wheels pass by station S' the parts all assume their normal positions, and it is obvious that they will be reversely operated by a train passing in the opposite direction to that heretofore described. From what has been said it will be seen that inasmuch as the signals are all normally at "danger" if there is a train in the block said signals cannot be operated, and hence the engineer is at once notified, whereas if the track is clear each signal can in turn be brought to "safety," whereupon the engineer is apprised that the track is clear.

In the form illustrated in Fig. 4 I have illustrated but one signal at each station S S'. In this form the wires d', d^2 of the signal at station A are connected, respectively, one to the electrode f and the other to one of the rails F of the main track. A battery 1 is connected at one pole to a wire f' , which in turn is connected to wire d^2 , the other pole of said battery being connected by a wire f^2 to an electrode f^3 , against which a pivoted arm or armature f^4 is normally held by means of a magnet f^5 , the pivoted end of said armature being connected by means of a wire f^6 to the other rail F' of the main track. Magnet f^5 receives its current from a battery 2', the poles of which are connected to the rails F' of a short track-section F', said magnet being connected to said rails by wires f^7 . Station S' is identical with station S in every way, except the parts are reversed. As the wheels of a train pass onto track-section F' battery 2 is short-circuited, allowing armature f^4 to contact with electrode f , whereupon the current from battery 1 of station S' will operate the signal A at station S by passing through the armature

f^4 of the former station to the rail F' and thence through armature f^4 of station S to electrode f and thence to the signal, said current returning to the battery at station S' through rail F . As the wheels pass onto the main tracks F F' the battery 1 of each signal-station S S' will be short-circuited, thus preventing any operation of the signals at said stations until after the wheels pass onto track-section F^3 of station S' , whereupon the signal at said latter station will be operated by the battery at station S in the same manner as heretofore described. It is obvious that a train moving in the opposite direction would first operate signals at station S' and then that at S .

In Fig. 5 I have illustrated the preferred form of my invention employed in connection with a continuous block system. In this form 20 G G' represent the rails of one block-section, G^2 G^3 those of another, and G^4 G^5 those of a third. I have, however, only illustrated the two signal-stations S S' , and as each of said stations is an exact duplicate one of the other 25 the description of one will suffice. The track G of the first block-section is connected by a wire g to a battery 10 at station S , the other pole of said battery being connected by a wire g' to an electrode g^2 , against which a pivoted 30 armature g^3 is normally held by a magnet g^4 , which is energized by a battery 11, having electrical connections with the rails g^5 of a short track-section g^6 , said tracks being connected by suitable wires g^7 to said magnet. 35 The armature g^3 is electrically connected at g^8 to a second armature g^9 , which is normally held in contact with an electrode g^{10} by means of a magnet g^{12} , which is energized by a battery 12 of a short track-section g^{13} . The electrode g^{10} is connected by a wire g^{14} to the track G' of the first block-section. The wires g and g^{14} of station S' are connected, respectively, to the tracks G^2 G^3 of the second block-section, and so on. Adjacent armatures g^3 and g^9 are pivoted two arms g^{15} g^{16} , which are electrically connected at g^{17} . Arm g^{15} is secured to armature g^3 , is insulated, and moves with armature g^3 ; also arm g^{16} is secured to armature g^9 in the same manner as g^3 and g^{15} , the 40 arm g^{15} being normally held in contact with an electrode g^{18} by magnet g^4 , said electrode being connected by a wire g^{19} to the track G^3 . The arm g^{16} is normally held by a magnet g^{20} in contact with an electrode g^{21} , which is connected by a wire g^{21} to a battery 13, the other pole of which is connected by a wire g^{22} to track G^2 . Opposite electrode g^{20} is a second electrode g^{23} , to which is connected the wire d' of signal A, the wire d^2 of the latter being 45 connected to wire g^{23} . Opposite electrode g^2 is a second electrode g^{24} , which is connected to wire d^2 of signal A', the other wire d' of said signal being connected to wire g . The wires g^{19} and g^{22} of station S' are connected, 50 respectively, to the tracks G^5 G^4 of the third block-section.

In operation a train passing from the first

block-section onto track-section g^{13} will cause battery 12 to be short-circuited, thus allowing the armature and arm g^9 g^{16} to move from their normal positions, the arm g^{16} contacting with electrode g^{23} and operating signal A of station S , said operation being effected by the current from battery 10 of station S' . As the wheels pass onto short section g^6 and the battery 11 thereof is short-circuited, allowing armature g^3 and arm g^{15} to move and open the circuit of batteries 10 and 13 at station S , armature g^3 contacting with electrode g^{24} , whereupon signal A' of station S will be operated by the battery 13 of the first block-section. As said wheels pass onto the tracks of the second block, the armatures g^3 g^9 and arms g^{15} g^{16} at station S all resume their normal positions under the influence of magnets g^4 g^{12} , closing the circuit of batteries 13 and 10 of station S . It will be noted that the batteries 10 and 13 of each signal-station are opposed to each other, so that when the signals are not being operated said batteries will not waste. The wheels of the train in passing over the main tracks of each block-section short-circuit the batteries 10 and 13, and thus prevent any operation of the signals at either of the stations S S' , as heretofore fully set forth. It will be specially noted that the form shown in Fig. 5 and just described is for use only upon a single-track system, where the trains move in opposite directions on the same track, and it is clear that the signals of each station will act successively no matter in which direction a train may be moving.

The form shown in Fig. 6 is identical with that just described, except that the double signal, such as is illustrated in Fig. 1, is employed in lieu of a single signal on each side of the track, as in Fig. 5, wires 10 13 being employed as conductors for the batteries 10 and 13 instead of the tracks of the block-sections. In this form the track-sections g^6 and g^{13} are made somewhat longer than the same sections illustrated in Fig. 5.

In Fig. 7 I have illustrated the same system as described in Figs. 5 and 6 as adapted for use on double tracks—that is, tracks upon which the train moves only in one direction—which in the present instance I have indicated by the arrow h . In this form the parts illustrated in dotted lines are entirely omitted, as only one signal is necessary at each station, the signal at each station being operated by the battery 10 of next station ahead in the manner heretofore fully set forth.

Should the road-bed between the rails of sections g^6 g^{13} of the signal-stations offer insufficient insulation and thereby short-circuit the battery of any of said sections, said short-circuiting is overcome by subdividing a section of track into sufficiently short insulated subsections, as shown at $h' h^2 h^3$, Fig. 8. The rails of each of said subsections is electrically charged by a battery h^4 , which serves to energize a magnet h^5 . The magnet of each section normally holds an arm or armature h^6 .

in contact with an electrode h^7 , which is connected by a wire h^8 to one pole of battery h^4 . The pivoted end of arm or armature h^6 is connected by a wire h^9 to one rail h^{10} of said subsection, the other pole of said battery being connected to the rail h^{12} thereof. When wheels pass from section g^{13} onto subsection h' , said wheels operate the track-circuit of said subsection by shunting the magnet h^5 thereof, and the signals are operated, as hereinbefore described. As said wheels pass onto subsection h^2 the circuit thereof is opened, allowing the armature h^6 of section h' to move away from its electrode, and this operation continues until said wheels move from subsection h^3 onto the section g^{13} of the next signal-station, all the track-circuits of said subsections remaining open as long as the wheels of the train are on any one of said subsections, thereby preventing the current from reaching the subsections already passed over and avoiding waste of the batteries. It is obvious that the above-described operation takes place no matter which way the train may be moving.

In Figs. 9 and 10 I have shown the arrangement of my system where it is necessary to make a switch in the railway-track. In the form illustrated in Fig. 9 the track of the main section is divided into a subsection I where the switch-rails i are about to join the rails of the main section. The switch is normally operated by an arm i' , pivoted at any suitable point and designed to contact normally with the right-angular arm i^2 of a pivoted arm or member i^3 , which is connected at i^4 to a wire i^5 , which in turn is connected to one track—say G' —of one of the block-sections, said track being electrically connected to the battery 13 of one of the signal-stations. (Illustrated in Fig. 5.) The other rail, G , of said track is also connected to said battery, and adjacent subsection I is connected by a wire i^6 , at one end of which is connected an electrode i^7 , against which is designed to normally contact a pivoted arm i^8 , connected by an insulated pitman i^9 to the arm or member i^3 . It will be noted that the subsection I has no electrical connection whatever with the signaling system. The other end of arm i^8 is connected by a wire i^{10} to said rail G on the other side or to the right of the subsection I. The wire d^2 of signal A is connected to track G' to the right of subsection I and also by a wire i^{12} to an electrode i^{13} , against which arm or member i^3 is designed to normally contact. The wire d^2 of signal A' is connected to track G at the junction therewith of wire i^6 . The wire d^1 of signal A is connected to an electrode i^{14} , located opposite electrode i^7 , while the corresponding wire of signal A' is connected to an electrode i^{15} opposite electrode i^{13} . From this it will be seen that as soon as the switch-lever i' is moved arms i^3 and i^8 will contact, respectively, with electrodes i^{14} and i^{15} , thereby closing the electric circuits from the battery 13 of the station on the left of the

switch and of battery 10 on the right of the switch, whereby the signals will be operated, as hereinbefore described.

In Fig. 10 I have shown a slightly-modified form of the foregoing, but one signal being used. In this form the switch-lever i' holds the end j of an arm or lever J normally in contact with an electrode j' , which is electrically connected by a wire j^2 to the rail G' , leading from signal-station S, (illustrated in Fig. 5,) the wire d^2 of signal A being also connected to said rail at the same point. The section of rail G' leading to station S' (not shown) is connected to arm J by a suitable wire j^3 . The current from rail G is passed around subsection I by means of a wire j^4 , connected at one end to said rail, the other end thereof being connected to a pivoted arm or armature j^5 , adapted to normally contact with an electrode j^6 , connected by a wire j^7 to the section of track G leading to station S'. (Not shown.) Opposite electrode j^6 is located an electrode j^8 , to which the wire d^1 of signal A is connected. At the junction of wire j^7 with track G is connected a wire j^9 , leading to a magnet j^{10} , from which a second wire leads to an electrode j^{12} , opposite electrode j' . The operation of the switch-lever i' allows arm or lever J to contact with electrode j^{12} , thereby energizing magnet j^{10} from battery 10, station S', whereupon the same will attract armature j^5 , which will contact with electrode j^8 , whereupon the battery from station S (not shown) will operate the signal. As the train passes onto the main track the track-currents will be short-circuited and the signal at the switch kept from operating in the manner heretofore fully described.

The advantages and operation of my improved railway-signal will be apparent from what has been said to those skilled in the art to which it appertains. It will be specially observed that all liability of accident is reduced to a minimum by the use thereof and that the same is exceedingly economical in battery consumption, because battery b^7 is only in use when disk is rotating to clear position, and disk is held in clear position by magnet D and of the normally-opposed batteries of the signal-circuits. For instance, it will be seen, by reference to Figs. 3 and 4, that battery 1, station S, and battery 1, station S' oppose each other when the system stands normal, as do batteries 10 and 13, Figs. 5 and 6. Tracing the circuit in Fig. 4 when system stands normal battery 1 at station S, beginning with the copper pole, to wire f' , to rail F, to wire f' at station S', to copper pole, zinc pole, (station S'), wire f^2 , armature f^4 , to rail F', to armature f^4 , (station S,) wire f^2 to zinc pole, the batteries standing normally copper to copper, zinc to zinc.

It will be understood, of course, that while I have shown and described the disks normally covering the openings it is evident I could employ the rail or wire circuit systems that will normally hold the disks away from

the openings; also, that more than a single armature could be used on lever C and both poles of magnet utilized in drawing the said lever to close contact; also, that the usual 5 semaphore-arms could be substituted for the disks.

I claim as my invention—

1. The herein-described railway-signal, comprising a casing having holes or openings 10 therein, a rod or arm rotatably mounted in said casing and having disks thereon adapted to normally cover said openings, a magnet and its armature adapted to rotate said rod or arm, an electric circuit adapted to energize 15 said magnet, a hook-arm on said rod or arm adapted to open the circuit to said magnet during the rotation of said rod or arm, and means for holding said disks away from said 20 openings, whereby said circuit is kept open, substantially as set forth.

2. The herein-described improved railway-signal, comprising a casing having holes or 25 openings therein, a rod or arm rotatably mounted in said casing and having disks thereon adapted to normally cover said openings, a motor adapted to rotate said rod or arm, a battery adapted to energize said motor, a spring contact-arm in circuit with said battery and adapted to be engaged by said rod or 30 arm, whereby the circuit from said battery is broken, and means for holding said disks away from said openings, substantially as set forth.

3. The herein-described improved railroad-signal, comprising a casing having holes or 35 openings therein, a rod or arm rotatably mounted in said casing and having disks thereon adapted to normally cover said openings, a motor adapted to rotate said rod or arm, a battery adapted to energize said motor, a spring contact-arm in circuit with said battery, a hook arm or member secured on said 40 rod or arm and adapted to engage said spring contact-arm, whereby the circuit from said battery is broken, and means for holding said disks away from said openings, whereby said 45 circuit is kept open, substantially as set forth.

4. The herein-described railway-signal, comprising a casing having holes or openings 50 therein, a rod or arm pivotally mounted in said casing and having disks adapted to normally cover said openings, a magnet and its armature adapted to rotate said rod or arm, a battery adapted to energize said magnet, a 55 spring contact-arm connected to said battery and adapted to be engaged by said rod or arm, a pivoted contact-arm adapted to keep the circuit from said battery normally open, and an electrode with which said contact-arm is 60 designed to contact, substantially as set forth.

5. The herein-described railway-signal, comprising a casing having holes or openings 65 therein, a rod or arm rotatably mounted in said casing and having disks adapted to normally cover said openings, a magnet and its armature adapted to rotate said rod or arm, a battery adapted to energize said magnet, a

spring-arm in circuit with said battery and adapted to be engaged by said rod or arm, whereby said circuit will be opened by the rotation of the latter, and a pivoted contact-arm adapted to keep the circuit from said battery normally open, substantially as set forth. 70

6. The herein-described railway-signal, 75 comprising a casing having holes or openings therein, a rod or arm pivotally mounted in said casing and having disks adapted to normally cover said openings, a motor adapted to rotate said rod or arm, a battery adapted 80 to energize said motor, a pivoted contact-arm mounted adjacent said motor, and a counter-balancing-weight secured thereto, whereby the circuit to said motor is normally kept open, substantially as set forth. 85

7. The herein-described railway-signal, comprising a casing having holes or openings therein, a rod or arm pivotally mounted in said casing and having disks adapted to normally cover said openings, a motor adapted 90 to rotate said rod or arm, a battery adapted to energize said motor, a pivoted contact-arm adapted to keep the circuit to said motor normally open, and a magnet adapted to attract the armature on the lower end of said contact-arm, whereby said circuit will be closed, substantially as set forth. 95

8. The herein-described railway-signal, comprising a casing having holes or openings therein, a rod or arm pivotally mounted in 100 said casing and having disks adapted to normally cover said openings, a motor adapted to rotate said rod or arm, a battery adapted to energize said motor, a spring contact-arm adapted to be engaged by said rod or arm, 105 an armature secured to said rod or arm, a pivoted contact-arm adapted to keep the circuit to said motor normally open, an electrode with which said contact-arm is adapted to contact, and a magnet adapted to attract the 110 armature of said rod or arm and the armature on the lower end of said pivoted contact-arm, substantially as set forth.

9. The combination with a plurality of batteries supplying normally-opposed signal-currents through the same conductors, and circuit-controllers designed to govern said circuits and adapted to be operated by the wheels of a passing train, of a plurality of signals, an electric battery adapted to operate each of said signals, and a circuit-controller for each of said batteries adapted to be operated by one of said signal-currents, substantially as set forth. 115

10. The combination with a plurality of batteries supplying normally-opposed signal-currents through the same conductors, circuit-controllers designed to control said currents, magnets adapted to operate said circuit-controllers, and batteries adapted to energize said magnets, said batteries being adapted to be short-circuited by the wheels of a passing train, of a plurality of signals, an electric battery adapted to operate each of 120 125 130

said signals, and a circuit-controller for each of said batteries adapted to be operated by one of said signal-currents, substantially as set forth.

5 11. The combination with an insulated block or section of track, of a plurality of batteries supplying normally-opposed neutralizing signal-currents through the same conductors to a plurality of signal-stations, each station having two signals, circuit-controllers adapted to govern said circuits, electrically-charged subsections of track arranged in continuation of said former block or section, magnets in circuit with said subsections and 15 adapted to normally attract said circuit-controllers, and means for neutralizing said magnets, whereby but one of said signals will be operated at a time, substantially as set forth.

12. The combination with an insulated block or section of track, of a plurality of batteries supplying normally-opposed neutralizing signal-currents through the same conductors to a series of signal-stations, each station having two signals, and circuit-controllers formed each of electrically-connected members pivoted adjacent each other and adapted to be operated by the wheels of a passing train, whereby the circuits of said batteries will be changed and only one signal 25 at each station will be operated at a time, as set forth.

13. The combination with an insulated block or section of track, of batteries supplying normally-opposed neutralizing signal-currents through the same conductors to a series of signal-stations, each station having two signals, and an electrically-governed circuit-controller for each circuit formed of a plurality of electrically-connected members pivoted adjacent each other and adapted to be operated by the wheels of a passing train, whereby but one signal at each station will be operated at a time, as set forth.

14. The combination with an insulated block or section of track, of batteries supplying normally-opposed neutralizing signal-currents through the same conductors to a series of signal-stations, each station having two oppositely-arranged signals, circuit-controllers 45 for each circuit formed of a plurality of electrically-connected members pivoted adjacent each other, magnets for governing said circuit-controllers, and means for neutralizing said magnets, whereby but one of said signals at each station will be operated at a time, substantially as set forth.

15. The combination with an insulated block or section of track, of batteries supplying normally-opposed neutralizing signal-currents through the same conductors, circuit-controllers for each circuit formed of a plurality of electrically-connected members pivoted adjacent each other, an electrically-charged subsection of said track adjacent 60 each of said circuit-controllers, magnets in circuit with said subsections and adapted to govern said circuit-controllers, and means for

neutralizing said magnets, whereby said circuits will be changed, substantially as set forth.

16. The combination with a series of insulated blocks or sections of track, of batteries supplying normally-opposed neutralizing signal-circuits for each of said blocks or sections, a circuit-controller for each of said circuits 75 comprising a plurality of electrically-connected movable members pivoted adjacent each other, electrically-charged subsections of track located between and arranged in continuation of said insulated blocks or sections, 80 magnets in circuit with said subsections and adapted to attract said circuit-controllers and keep said signal-circuits normally closed, and means for short-circuiting said magnets, substantially as and for the purpose set forth. 85

17. The combination with a series of insulated blocks or sections of track, of two signals located adjacent to the terminals of each of said blocks or sections, batteries supplying normally-opposed neutralizing signal-circuits 90 to said signals, a circuit-controller for each of said circuits, comprising a plurality of electrically-connected movable members pivoted adjacent to each other and adapted to keep said circuits normally closed, and means for 95 operating said circuit-controllers whereby said circuits will be changed and but one signal of each series will be operated at a time, substantially as set forth.

18. The combination with a series of insulated blocks or sections of track and two signals located adjacent the terminals of each of said blocks or sections, of a plurality of batteries supplying normally-opposed signal-circuits to each of said blocks or sections, circuit-controllers for each of said circuits formed each of two parts or members, magnets adapted to normally attract both arms of each circuit-controller, and means for short-circuiting 105 said magnets, whereby but one signal will be 110 operated at a time, substantially as set forth.

19. The combination with a series of insulated blocks or sections, of a plurality of batteries supplying normally-opposed signal-circuits to each of said blocks or sections, circuit-controllers for each of said circuits formed each of two pivoted arms or members, two or more subsections of said track, means for 115 electrically charging the same, magnets in circuit with each of said subsections, each of said 120 magnets being adapted to attract one arm of each of said circuit-controllers, and means for short-circuiting said batteries, whereby all 125 of said circuits are consecutively opened.

20. The combination with an insulated block 125 or section of track having a switch in connection therewith, of batteries supplying normally-opposed signal-circuits to said block or section, the switch-lever, conductors for causing said circuits to pass around said switch, 130 and a circuit-controller operated by said switch-lever, whereby the circuits through said conductors are opened, as and for the purpose set forth.

21. The combination with an insulated block or section of track having a switch in connection therewith, of batteries supplying normally-opposed signal-circuits to said block or section, the switch-lever, conductors for causing said circuits to pass around said switch, a circuit-controller connected to said conductors, and a second circuit-controller adapted to be operated by said switch-lever, whereby said former circuit-controller is operated, as and for the purpose set forth.
22. The combination with an insulated block or section of track having a switch in connection therewith, of batteries supplying normally-opposed signal-circuits to said block or section, the switch-lever, conductors for

causing said circuits to pass around said switch, a circuit-controller connected to one of said conductors, a second circuit-controller adapted to be operated by said switch-lever and connected to the other circuit-controller, and a magnet adapted to be energized by the operation of said second circuit-controller and designed to operate said first-mentioned circuit-controller, whereby a signal will be operated, substantially as set forth.

In testimony whereof I affix my signature in presence of two witnesses.

BARNEY SAMUELS.

Witnesses:

FRANK B. SCHNEIDER,
GEORGE W. HINTON.
